(57) **CLAIM**

The ornamental design for a surgical stapler deck with tissue engagement recess features, as shown and described.

DESCRIPTION

FIG. 1 is a perspective view of a surgical stapler deck with tissue engagement recess features, showing our new design; FIG. 2 is a first side elevational view of the surgical stapler deck of FIG. 1; and,

FIG. 3 is a second side elevational view of the surgical stapler deck of FIG. 1; and,
FIG. 4 is a top plan view of the surgical stapler deck of FIG. 1.

The broken lines immediately adjacent the shaded areas represent the bounds of the claimed design while all other broken lines are directed to environment and are for illustrative purposes only; the broken lines form no part of the claimed design.
